Primary Examiner — Leanne Was-Engelhart(74) *Attorney, Agent, or Firm* — McGlew and Tuttle, P.C.(57) **CLAIM**

The ornamental design for an awning, as shown and described.

DESCRIPTION

FIG. 1 is a front view of an awning, showing my new design;
 FIG. 2 is a rear view thereof;
 FIG. 3 is a top view thereof;
 FIG. 4 is a bottom view thereof;
 FIG. 5 is a lateral view (right side) thereof;
 FIG. 6 is a lateral view (left side) thereof; and,
 FIG. 7 is a perspective view thereof.

The broken lines depict portions of the awning that form no part of the claimed design.
